FOLDING GANTRY FOR CRANES

John E. Callouette and Revillo F. Kinney, Marion, Ohio
Application January 14, 1953, Serial No. 331,163

5 Claims. (Cl. 212—59)

The invention relates generally to material handling power cranes, and more particularly to the mechanism for providing a new improved rapid folding boom supporting gantry.

This rapid folding gantry is composed of flexible back legs which make up the sloping member and are pivotally connected to the upper rear horizontal member or aft support of a stationary frame mounted on the machinery deck. The front ends of these flexible legs are pivotally connected to the top of the front telescoping legs or the vertical member with yoke-like feet supported on and latched to the fore support on said frame which operates with the gantry in telescopic extended position. This vertical member can be guided and controlled into a folded position and returned to the extended positions by raising and lowering the boom by means of a boomhoist line wound upon a conventional controlled winch. Two winches may be employed if greater speed is desired. Both winches would be powered from a common source, such as an internal combustion engine mounted on the deck of the crane.

One of the objects in view is to provide improved means for folding and extending the gantry by controlled power through operating the boom, necessitating only human guidance and control instead of the present day methods that require human lifting of gantry parts to extend and fold.

Another object is to provide means for lowering the gantry and boom to the elevation to and below the top of the cab to obtain overhead clearance, more quickly, and with greater safety and with the least amount of human effort.

Still another object is the provision of means for maintaining the maximum angle between the boomhoist line and the boom, thus keeping the line and boom loads to a minimum for all working angles of the boom, accomplished by the telescoping action of the front legs of the gantry.

Another object is the provision of latch pins to latch the yoke-like feet of the male member of the telescoping front legs of the gantry to the said frame, which pins when removed to unlatch the feet of the front legs, are used to latch the front legs from telescoping, so that the feet of the front legs will lift clear of the front member of supporting frame when the boom is lifted to a high position, permitting the front and back legs to automatically fold progressively towards parallel positions as the boom is lowered into a horizontal plane at cab height.

Another object is the provision of ellipsoidal saddles mounted on upper front frame member upon which the flexible back leg of the gantry rides, being longer than the upper side members of the frame, when the boom and gantry are lowered to the elevation of the top of the cab.

Another object is the provision of inverted channel upper side supporting frame members which act as guides to automatically fold the front legs back and under as the boom is lowered with the feet of the front legs unlatched,

2

the telescopic action latched and the front legs swung rearwardly.

Other novel features of construction and arrangement of parts will appear from the following description and claims.

In the accompanying drawings, wherein is illustrated a practical embodiment of the principles of the invention:

Fig. 1 is a side elevation illustrating the structure of a crawler crane with the gantry extended to its initial working position.

Fig. 2 is an isometric illustration of the gantry extended to its initial working position as shown in Fig. 1.

Fig. 3 is a side elevation illustrating the structure of a crawler crane with the gantry fully extended.

Fig. 4 is an isometric illustration of the gantry fully extended as shown in Fig. 3.

Fig. 5 is a side elevation illustrating the structure of a crawler crane with the gantry raised.

Fig. 6 is an isometric view of the gantry structure as shown in Fig. 5.

Fig. 7 is a side elevation illustrating the structure of a crawler crane with the gantry folded and boom lowered to the elevation of the top of the cab.

Fig. 8 is an isometric illustration of the folded gantry as shown in Fig. 7.

Referring to the drawings, 20 indicates the machinery deck of the crane, which, as is common practice, is rotatably mounted on a vertical axis on an undercarriage of either portable frame, truck or crawler, and provided 30 with a motor for selectively propelling the carrier, swinging the superstructure, hoisting a load and operating the boom and gantry. 21 indicates the stationary machine side frames, which are also the front legs of the stationary frame supports of the folding gantry or A frame. The 35 back members 22 of the stationary frame and the upper side members 23, together with the back upper horizontal member 24 and the front upper horizontal member 25 constitute the supports and complete the stationary frame.

26 indicates the flexible back legs on the rear member of the folding gantry and the telescoping front legs on the front member 27. 28 is the crossbracing of the female members of the telescoping front legs or front member. Latch pins 29 are inserted through holes at the ends of the 45 bifurcated foot to prevent the male members of the front legs from losing their footing when the boom is raised to a high enough position to extend the telescoping of the front legs. The telescoping front legs have the holes 30 into which the pins 29 are transferred to unlatch the feet of the front legs from the support shaft 19 and latch the front legs to prevent their telescoping and to allow them to raise their feet off the shaft 19 as the boom is raised to a high position.

The support shaft 19 forms the fore support for the 55 folding gantry A frame and the back member 24 forms its aft support. It will be noted that these fore and aft supports are spaced closer together than the length of the rear member or legs 26, as the sheaves 34 are beyond the saddle members 31 when the gantry is folded as shown 60 in Fig. 8. The front member 27 slopes back to connect with the rear member 26 at the apex. Thus, when the pins 29 are withdrawn from the bifurcated feet of the legs 27 and are inserted in the holes 30 they prevent the front member from telescoping. The boom is raised as shown 65 in Figs. 5 and 6, and the front member 27 hangs vertically and not over the shaft. As the boom is lowered, the front members 27 are pushed back with the bifurcated feet engaging the horizontal flange of the angle members 23 which guide them rearwardly to the lowered and folded position as shown in Fig. 8. The boom may be raised to unfold and extend the gantry at which time the bifurcated

feet are guided onto the shaft and latched as shown in Fig. 2.

32 indicates a conventional crane boom operated by the boomhoist and gantry operating cable 33 which is woven over the boomhoist sheaves 34. The ends of the cable 33 are attached to and wound upon the boomhoist winches 35 and 36 which are used when greater speed is desired, for raising and lowering the boom and for folding the rapid folding gantry.

We claim:

1. A rapid folding gantry for a hoist comprising a machinery deck, a boom pivoted to the front end of said deck, supports on said deck to the rear of said boom pivot, a fore mounting and an aft mounting on said supports, a foldable flying gantry having front legs and rear legs pivotally connected together at their upper ends to form an apex, said front legs having telescopic sections, a detachable pin to lock the telescopic sections of the front legs together, sheave means on said apex, detachable means to releasably connect the bottom of the front legs to said fore mounting, pivot means to pivotally connect the bottom of said rear legs to said aft mounting, a boom hoist line reeved over said sheave means and connected to said boom, winch means carried by said machinery deck to operate said boom hoist line to raise and lower the boom, the length from the attachment of said boom hoist line to the boom pivot being proportioned relative to the position of said aft mounting to provide a straight line of force between the attachment of said boom hoist

line with the boom and said aft mounting, which straight line of force lies above the normal position of said apex when said boom is elevated to provide a force to lift the locked telescopic sections of the front legs of the flying gantry and permit them to be disconnected from the fore mounting of said supports and folded back when the boom is lowered.

2. The structure of claim 1 is characterized in that the telescopic sections of said front legs of the flying gantry are expandable when unlocked to maintain said apex in alignment with said force line along said boom hoist line.

3. The structure of claim 1 is characterized in that said detachable means releasably connecting the bottom of the front legs to said fore mounting are bifurcated members having pins to hold them from becoming detached.

4. The structure of claim 1 is characterized in that said rear legs are flexible intermediate of the ends thereof.

5. The structure of claim 4 which also includes saddle means carried by said supports to receive the flexible rear legs of the flying gantry when folded.
